UNITED STATES PATENT OFFICE.

SAMUEL BOZEN, OF STERLING, ILLINOIS, ASSIGNOR TO J. B. SMITH, OF STERLING, ILLINOIS.

WEDGE-CUTTING MACHINE.

No. 839,716.

Specification of Letters Patent.

Patented Dec. 25, 1906.

Application filed February 1, 1906. Serial No. 298,953.

To all whom it may concern:

Be it known that I, SAMUEL BOZEN, residing at Sterling, in the county of Whiteside and State of Illinois, have invented certain new and useful Improvements in Wedge-Cutting Machines; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to machines for cutting wedges from blocks of wood, and is not only novel but is quite simple and can be manufactured with little expense.

When carriages and similar vehicles have been used for a time, the spokes in the wheels frequently become loose in the felly and it becomes necessary to tighten them by forcing small wedges into the outer ends of the spokes. These wedges are generally constructed of wood and are usually formed with a draw-shave on the end of a piece of wood of suitable size, the completed wedge being then sawed from the stick. My device is designed to manufacture such wedges with considerable rapidity and little labor, dispensing with the laborious operation just mentioned.

In the drawings, Figure 1 is a side elevation of my device, partly in section. Fig. 2 is a front elevation thereof with the operating-lever removed. Fig. 3 is an enlarged detail showing the manner of operation of the device.

Similar numbers refer to similar parts throughout the several figures.

1 represents a perpendicular block provided at its lower end with a shank 2, by means of which such block can be suitably attached to a bench or held at a desired height in a vise. On the front face of the block 1 are fixed a pair of guides 3, between which and the block 1 a knife 4 has vertical movement. The knife 4 is provided with a shank 5 integral therewith, the upper end of such shank being pivoted to a hand-lever 6, ful-

crumed on a bracket 7, fixed to the upper end 50 of the block 1.

In the front face of the block 1 is a wedge-shaped recess 8, and in the rear wall of such recess is an annular recess 9, holding a coiled spring 10, one end of which normally projects 55 beyond the wall of the recess 8. Projecting from the front face of the block 1, just below the recess 8, I provide a support 11, preferably integral with block 1.

The lower edge of the knife 4 is beveled on 60 the outer face—that is to say, the face away from the block 1—so that in the operation thereof the cutting edge of the knife passes along the face of such block.

To operate the device, the lever 6 is raised 65 until the blade of the knife clears the recess 8 and a block 12 of wood inserted into the recess, as shown in Fig. 3, the thickness of the block 12 being such as to permit the passage thereof between the guides 3. The 70 knife 4 is then forced downwardly, cutting a wedge-shaped piece 13 from the end of the block 12. The grain of the wood in the block 12 is transversely of the block, as indicated by the small arrow above the same, the 75 cutting of the wedge being thereby rendered more easy. In the downward movement of the knife 4 the force of the operation tends to break a wedge-shaped piece 14 from the end of the block 12, leaving the end of such block 80 square and ready for the formation of the next succeeding wedge.

When the knife 4 is raised after the wedge has been cut from the block of wood, such wedge is expelled from the recess 8 by the 85 spring 10.

I do not wish to be understood as limiting myself to the manufacture of wedges of the class herein mentioned, as wedges of varying sizes and shapes and which can be used in 90 various places aside from the one referred to are capable of being formed by mechanism similar to that shown and described herein.

What I claim as my invention, and desire to secure by Letters Patent of the United 95 States, is—

In a device of the class described, the combination of an upright block fashioned into a

shank at one end and provided with a recess in one of its faces, the bottom of said recess being inclined to the face of the block and having a depression therein, a pair of guides or ways attached to the face of the block in which said recess is formed, a knife movable in said guides, a bracket fixed to the upper end of said block, a hand-lever pivoted to said bracket and to the knife, a support 11

upon the block under the recess, and a spring seated in said depression in the bottom of the recess. 10

In testimony whereof I affix my signature in presence of two witnesses.

SAMUEL BOZEN.
